(57) **CLAIM**

The ornamental design for burner head, as shown and
described.

DESCRIPTION

FIG. 1 is a front perspective view of a burner head according
to a first embodiment of the present disclosure;

FIG. 2 is a top perspective view, rotated 45 degrees, of the
burner head of FIG. 1;

FIG. 3 is a first side view of the burner head of FIG. 1;

FIG. 4 is a second side view, rotated 90 degrees, of the burner
head of FIG. 3;

FIG. 5 is a third side view, rotated 180 degrees, of the burner
head of FIG. 3;

FIG. 6 is a fourth side view, rotated 270 degrees, of the burner
head of FIG. 3;

FIG. 7 is a front perspective view of a burner head according
to a second embodiment of the present disclosure;

FIG. 8 is a top perspective view, rotated 45 degrees, of the
burner head of FIG. 7;

FIG. 9 is a first side view of the burner head of FIG. 7;

FIG. 10 is a second side view, rotated 90 degrees, of the burner
head of FIG. 9;

FIG. 11 is a third side view, rotated 180 degrees, of the burner
head of FIG. 9;

FIG. 12 is a fourth side view, rotated 270 degrees, of the
burner head of FIG. 9;

FIG. 13 is a front perspective view of a burner head according
to a third embodiment of the present disclosure;

FIG. 14 is a top perspective view, rotated 45 degrees, of the
burner head of FIG. 13;

FIG. 15 is a first side view of the burner head of FIG. 13;

FIG. 16 is a second side view, rotated 90 degrees, of the burner
head of FIG. 15;

FIG. 17 is a third side view, rotated 180 degrees, of the burner
head of FIG. 15;

FIG. 18 is a fourth side view, rotated 270 degrees, of the
burner head of FIG. 15;

FIG. 19 is a front perspective view of a burner head according
to a fourth embodiment of the present disclosure;

FIG. 20 is a top perspective view, rotated 45 degrees, of the
burner head of FIG. 19;

FIG. 21 is a first side view of the burner head of FIG. 19;

FIG. 22 is a second side view, rotated 90 degrees, of the burner
head of FIG. 21;

FIG. 23 is a third side view, rotated 180 degrees, of the burner
head of FIG. 21; and,

FIG. 24 is a fourth side view, rotated 270 degrees, of the
burner head of FIG. 21.

The broken line showing of base structure, gas orifices, and
raised arrow shaped prong forms no part of the claimed
design.
